LOUIS E. BALTZLEY, OF GLEN RIDGE, NEW JERSEY.

BINDER.

1,388,140.

Specification of Letters Patent. Patented Aug. 16, 1921.

Application filed April 29, 1920. Serial No. 377,425.

To all whom it may concern:

Be it known that I, LOUIS E. BALTZLEY, a citizen of the United States of America, and a resident of Glen Ridge, Essex county, and 5 State of New Jersey, have invented certain new and useful Improvements in Binders, of which the following is a specification.

This invention relates to what are commonly known as temporary binders and the 10 general objects of the invention are to provide a device of this character of simple, practical construction, which will firmly grip and hold the papers or other articles to be retained, which can be quickly and 15 easily operated to grip or to release the inserted articles, which will hold equally as well a few or a large number of articles and which, possessing the above advantages, will consist of but relatively few, simple and 20 durable parts, be relatively inexpensive as to cost and be neat and attractive as to appearance.

These and other objects I have attained by a novel construction and relation of elements, involving in part, a pair of coöperating clamping jaws having rounded back portions which slide over each other to produce the jaw opening and closing movements and which are actuated for this purpose by a 25 sliding control member carrying a pin or pins working in relatively inclined and intersecting slots formed on said back portions.

Other novel and advantageous features of the invention will appear as the specification proceeds.

In the accompanying drawing forming a part of this specification, I have illustrated the invention embodied in a number of commercial forms, but wish it understood that 40 the invention may be applied to other uses than the ones disclosed and further, that the structure may be modified to suit various requirements, as will be clear from the scope of the appended claims.

45. In the drawing referred to:

Figure 1 is a perspective view of the binder constructed as a clip for holding loose papers and with the sliding back portion of one of the clamping jaws shown as partly 50 broken away to better illustrate the intersecting slots.

Fig. 2 is a front elevation looking in between the clamping jaws and showing the upper jaw broken away and partly in section and indicating also one of the connecting pins in section to disclose the special de-

sign thereof, which corresponds to the planes of the crossed slots.

Fig. 3 is an enlarged cross sectional view of the binder, showing the same as applied 60 to a board or backing.

Fig. 4 is a perspective view of this construction.

Fig. 5 is a perspective view showing the binder as mounted within a folder, the rear 65 walls of the folder being broken away to disclose the mounting of the binder therein.

Fig. 6 is an enlarged cross sectional view of this latter construction, with the cover indicated in dotted lines as folded back to 70 give complete access to the binder.

Fig. 7 is a broken perspective view of the invention as used as a clamp for a drawing board.

The jaw elements of the binder are designated 10 and 11 and these are provided, as possibly best shown in Fig. 3, with over-sliding curved back portions 12 and 13, arranged preferably on substantially concentric arcs and with the concave face at the 80 back of the clamp. Each jaw furthermore is shown as standing at an acute angle with respect to the normal plane of the curved back, as represented by a line 14, joining the opposite edges of the curvature in the back. 85 This construction enables the forward edges of the jaw to securely grip the inserted papers, even when the clamp is opened to the fullest extent, as indicated in Fig. 3.

The curved back members of the two jaws 90 are retained in their sliding relation and are held against relative longitudinal displacement by means consisting in the illustration of curved guards 15 at the ends of the inner back member 13, and indicated as 95 formed integrally therewith and as bent inwardly in the form of loops, so as to overlap the end portions of the outer back member 12.

The backs are shifted, in the present disclosure, to accomplish the opening and closing movements of the jaws, from a finger slide 16 longitudinally slidable over the outer back member 12 and carrying near its opposite ends the operating pins 17, working in the relatively inclined slots 18 and 19, formed on intersecting angles in the outer and inner back members.

This intersecting or crossed relation of the slots is particularly shown in Fig. 2, from 110 which view it will be apparent that when the operating pins 17 are shifted toward the

left in this figure, the back members will be further overlapped or "telescoped" to bring the jaws together and that the reverse movement of the operating pins will slide the 5 back members in a way to separate or open the jaws.

It will also be clear from Fig. 2 that there may be one, or a number of these pairs of relatively intersecting slots. It is desirable 10 to have at least two pairs and therefore, two operating pins, since by this construction the operating slide can be entirely supported by the pins, which as indicated in Fig. 3, be headed over at their inner ends as at 20 to 15 prevent disengagement from the slots. This latter view also shows how the sliding operating plate preferably is curved to fit the concavity of the outer back member, so as to "seat" therein and take up a very small 20 space at the back of the clamp.

Reverting to Fig. 2, attention is directed to the fact that the slots 18 in the outer back member and the slots 19 in the inner back member are in each case substantially 25 parallel, and further, that the operating pins 17 are substantially diamond shaped in cross section, having diagonally opposite substantially parallel faces to fit the reverse inclines of these slots. These structural features 30 retain the jaws substantially parallel and cause them to travel in substantial parallelism in both opening and closing movements.

The operating slide is provided with a 35 convenient handle or handles for operating the same. In the first form of the invention, I have illustrated the same in the form of rearwardly or outwardly projecting lugs 21 integrally formed at the opposite ends of 40 the slide and for convenience in operation, I have shown one of the back members, the inner one 13 in this instance, as provided with similar rearwardly projecting lugs 22, so that the slide may be actuated in opposite 45 directions by a pinching engagement of the fingers with the pair of lugs 21-22 at one or the other end of the clamp. This construction enables the necessary force to be easily applied, without shaking the clamp or 50 disarranging the papers inserted therein. The relatively fixed grips 22 also may be so located as to form stops limiting the movement of the slide in opposite directions.

From the description thus far, it will be 55 apparent that the clamp may be quickly opened or closed by simply exerting a pinching force on the coöperating pairs of grips 21-22 provided at the opposite ends thereof. The crossed slots are arranged on relatively slight inclines to the horizontal (Fig. 60 2), so that the pins or lugs working therein will securely hold the jaws in any position to which they have been set. The jaws are usually constructed of resilient or spring 65 material and this feature also aids mate-

rially in maintaining the jaws in the position to which they have been adjusted, since as the jaws yield more or less, the parts are caused to "bind" and hold all the more firmly.

In the first two forms I have shown the binder as used simply as a clip for loose papers or the like.

In Figs. 3 and 4, the binder is shown as permanently secured to a backing or board 70 23, as by means of tubular rivets 24 passed through the lower jaw 11 and secured in the material of the board. This provides a very handy clip by which loose papers may be quickly secured on a backing.

In Figs. 5 and 6 I have shown how the invention may be applied to a folder or book construction. Here the backing 25 to which the lower jaw is secured at 24 forms one cover of a book or folder structure 80 85 having a back 26 and a cover 27. To gain free access to the clip for operating the same to clamp or release papers held in the folder, the cover is turned back as indicated in dotted lines in Fig. 6. In this construction, 90 the binder has all the appearance of an ordinary book and possesses in addition the advantages of a quick operating temporary binder.

Another possible use of the invention is 95 disclosed in Fig. 7, wherein I have shown the under jaw of the clamp as secured by suitable fastenings 28 in a recess 29 in the edge of a drawing board 30, the upper clamping jaw 10 being exposed substantially 100 flush with the face of the board for the purpose of clamping a sheet of drawing paper. In this view also I have shown how the operating slide may have only a single grip or finger hold 21^a.

In addition to the advantages enumerated, the invention has the further important advantage that all the main parts may be constructed of sheet metal and are of such construction that they may be produced by simple stamping operations. The construction, furthermore, it will be seen, provides a particularly wide-opening clamp which enables 110 loose papers to be very readily engaged therein.

This wide-opening feature is particularly shown in Fig. 3 where, in the dotted lines, it will be noted that the binder will open up to the full height of the expanded back, or to a point where the jaws stand substantially parallel, the sliding back members being so designed as to stand in overlapping relation even in this fully expanded condition. As will also be apparent from this view, the curved backs of the jaws are drawn 120 on arcs from a center located to the rear of the binder, say at the point 31, from which it follows that the clamping edge of the jaw or jaws traverse a wider angle than the relatively movable backs.

In other words, the rotary movement of the backs is accentuated or multiplied so that a relatively slight movement of the backs may produce a much greater movement of the clamping edge of the jaws. By varying the center on which the arcuate backs of the jaws are formed, the proportionate movements of the backs and the clamping edges of the jaws may be altered 10 at will.

What I claim is:

1. A binder comprising coöperating clamping jaws having concentrically curved slidably engaging back portions arranged 15 with the concave sides thereof toward the outside of the binder and provided with relatively inclined slots arranged on intersecting planes and an operating member working in said relatively intersecting slots.

2. A binder comprising coöperating clamping jaws having rounded back portions riding one over the other and provided with relatively inclined slots arranged on intersecting planes and a slide confined to the 25 back portions and carrying a pin working in said slots, said pin being substantially diamond shaped in cross section and having diagonally opposite substantially parallel faces to fit the sides of the intersecting slots.

3. A binder comprising coöperating clamping jaws having rounded back portions riding one over the other and provided with relatively inclined slots arranged on intersecting planes and an operating member substantially diamond shaped in cross section 35 and having diagonally opposite substantially parallel faces fitting the sides of the intersecting slots.

4. A binder comprising coöperating clamping jaws having similarly curved back portions arranged with the concave faces thereof toward the outside of the binder riding one over the other and provided with relatively inclined slots arranged on intersecting planes, an operating member working 45 in said relatively intersecting slots and curved guides of substantially the same curvature as the back portions at the ends of one of the back portions engaging over the 50 ends of the companion back portion.

5. A binder comprising a pair of coöperating clamping jaws having backs sliding one over the other in the opening and closing movements of the jaws and provided 55 with relatively inclined slots arranged on intersecting planes, means for confining the backs against longitudinal shifting movement, operating means working in the intersecting slots for shifting the backs to open 60 and close the jaws, said operating means including a longitudinally shiftable slide, finger grips at the opposite ends of said slide and coöperating finger grips at the opposite ends of the jaws.

6. A binder comprising a pair of coöp-

erating clamping jaws having backs sliding one over the other in the opening and closing movements of the jaws and provided with relatively inclined slots arranged on intersecting planes, means for confining the 70 backs against longitudinal shifting movement and operating means working in the intersecting slots for shifting the backs to open and close the jaws and including pins substantially diamond shaped in cross section 75 and having diagonally opposite substantially parallel faces to fit the sides of the intersecting slots.

7. A binder comprising coöperating clamping jaws having rounded back portions 80 arranged with the concave sides thereof toward the outside of the binder and riding one over the other and provided with relatively inclined slots arranged on intersecting planes, an operating member working in said relatively intersecting slots and means for confining the jaws against relative longitudinal shifting movement.

8. A binder comprising coöperating jaws having curved back portions arranged with 85 the concave faces thereof at the back of the binder, an operating slide seated in said concavity at the back of the binder and pin and slot connections between said slide and back portions.

9. A binder comprising coöperating jaws having curved back portions arranged with the concave faces thereof at the back of the binder, an operating slide seated in said concavity at the back of the binder and pin 100 and slot connections between said slide and back portions, said slide being curved transversely to fit the curvature of the concavity in which it is seated.

10. A binder comprising coöperating jaws 105 having back portions movable one over the other in the opening and closing movements of the jaws, a longitudinally shiftable operating member at the back of the binder on the outside of the back portions of the jaws 110 and provided with finger grips at the opposite ends of the same projecting to the rear of the binder, pin and slot connections between said operating member and the back portions of the jaws and rearwardly projecting relatively stationary grips at the opposite ends of the binder substantially in line with the grips on the ends of the shiftable operating member.

11. A binder comprising coöperating jaws 120 having back portions movable one over the other in the opening and closing movements of the jaws, a longitudinally shiftable operating member at the back of the binder and provided with finger grips at the opposite 125 ends of the same, pin and slot connections between said operating member and the back portions of the jaws and relatively stationary grips at the opposite ends of the binder substantially in line with the grips on the 130

ends of the shiftable operating member, said stationary grips standing in the path of the shifting movement of the operating member to form stops therefor.

5 12. A binder comprising cooperating jaws having concave back portions slidable one over the other, curved guides at the ends of one of said back portions and overlapping the ends of the companion back portion, said

10 back portions having two pairs of relatively inclined slots arranged on intersecting angles, an operating slide seated in the concavity of the outer back portion, pins car-

ried by said slide and operating in the relatively intersecting slots, said pins having 15 heads at the inner face of the inner back portion to slidely confine the operating member to the outer face of the outer back portion, finger grips at the ends of the slideable operating member and companion relatively stationary finger grips projecting rearwardly from the guides aforesaid.

20 In witness whereof, I have hereunto set my hand this 26th day of April, 1920.

LOUIS E. BALTZLEY.
